UNITED STATES PATENT OFFICE.

WALTER K. PALMER, OF CROZET, VIRGINIA.

DESIGN FOR A DRAFTSMAN'S INSTRUMENT.

SPECIFICATION forming part of Design No. 24,042, dated February 12, 1895.

Application filed June 4, 1894. Serial No. 513,479. Term of patent 7 years.

To all whom it may concern:

Be it known that I, WALTER K. PALMER, a citizen of the United States, residing at Crozet, in the county of Albemarle and State of Virginia, have invented and produced a new and original Design for Drawing-Instruments, of which the following is a specification, reference being had to the accompanying drawing, which shows an instrument made according to my design, one view being considered sufficient.

My invention consists of a novel design for a thin, flat drawing instrument commonly known to the art as a "curve."

15 W denotes the main body-portion provided at its head-end N with a scroll N', which will be more minutely described hereinafter, and at its tail-end O with another scroll O' less pronounced in character.

20 The exact outline of the instrument consists of an hyperbolically curved end N having the point P at its pole, the latter being located in said end and in line with a straight edge H K.

The edge of the head-end is given a curve 25 A B C D R F which constitutes one portion of one edge of the instrument, and is the mathematical curve known as the hyperbolic, inverse, or reciprocal spiral.

H S represents part of the inner edge of the 30 scroll N' and forms, in conjunction with the curve A B C D R F an opening extending into the point or pole P, where it terminates in a sharp V-shaped recess. The point or pole P is at the vertex of the V-shaped recess. 35

The outline of the scroll of the tail-end of the instrument consists of the curves a b F and a d K.

What I claim is—

The design for a drawing instrument having the shape and configuration herein shown and described. 40

In witness whereof I affix my signature in the presence of two witnesses.

WALTER K. PALMER.
